GLUING MACHINE

Walter A. Saatman, Roslyn, Pa.

Application July 31, 1931, Serial No. 554,315

14 Claims. (Cl. 91—50)

The object of my present invention is to devise a novel gluing machine in which conventional tight wrap gluing can be accomplished by means of a conventional gluing roll which can be replaced by a novel stencil roll so that the same machine can be employed for the conventional gluing of wraps and for stencil work.

A further object of the invention is to devise novel means for actuating a novel construction of a gluing roll whereby the stencil mechanism will be operated at the proper time to effect the transverse gluing of the wraps.

A further object is to devise a novel roll which will continuously effect the longitudinal gluing of the wraps and intermittently effect the transverse gluing of the wraps.

In this art, as heretofore practiced, it has been deemed necessary in stencil work, to employ a separate and independent flat stencil machine, and the stencil machines have been constructed in such a manner that it has been impractical to combine them with a wrapping machine without materially slowing up production.

A further object of my present invention is to devise a single machine which can be employed for stencil work and also for conventional gluing, which will feed the glued wraps directly to a wrapping machine in such a manner that the wraps can be conveniently handled in a minimum of time by the operator of the wrapping machine.

With the above and other objects in view, as will hereinafter more clearly appear, my invention comprehends a novel gluing machine adapted for both conventional gluing and for stencil work.

It further comprehends a novel construction and arrangement of a gluing roll in which the gluing roll is driven in a novel manner, and wherein the paster feet carrying portion of the roll can be controlled in such a manner that the paster feet will be brought into and out of operation to contact at predetermined times with the wrap which is to be glued.

It further comprehends novel detent mechanism and novel means for actuating it.

Other novel features of construction and advantage will hereinafter more clearly appear in the detailed description and the appended claims.

For the purpose of illustrating the invention, I have shown in the accompanying drawings a typical embodiment of it, which, in practice, will give satisfactory and reliable results. It is, however, to be understood that the various instrumentalities of which my invention consists can be variously arranged and organized, and my invention is not limited to the exact arrangement and

organization of these instrumentalities as herein set forth.

Figure 1 is a top plan view of a gluing machine embodying my invention.

Figure 2 is an end elevation of the gluing machine.

Figure 3 is a section taken substantially on line 3—3 of Figure 1.

Figure 4 is a sectional view of the gluing roll and certain of its adjuncts, the section being taken substantially on line 4—4 of Figure 3.

Figure 5 is a section on line 5—5 of Figure 4.

Figure 6 is a sectional elevation of the trip mechanism on line 6—6 of Figure 4.

Figure 7 is a side elevation, partly in section, of the trip mechanism, certain of the parts having been removed for the sake of clearness of illustration, the section being taken on line 7—7 of Figure 4.

Figure 8 is a side elevation, partly broken away, to show more clearly the driving mechanism for the gluing mechanism.

Figure 9 is a section on line 9—9 of Figure 8.

Figure 10 is a plan view, showing more particularly, the gearing for driving the gluing rolls.

Figure 11 is a section on line 11—11 of Figure 7.

Figure 12A is a side elevation showing details of the construction.

Figure 12 is a view similar to Figure 6 but showing the parts in clutched position, the section being taken on line 12—12 of Figure 13.

Figure 13 is a section on line 13—13 of Figure 12.

Figure 14 is a section on line 14—14 of Figure 13, similar to Figure 7, but showing the parts in clutched engagement.

Figure 15 is a section on line 15—15 of Figure 16 showing the relation of the parts when lever 65 is drawn upwardly.

Figure 16 is a section on line 16—16 of Figure 15.

Similar numerals of reference indicate corresponding parts.

Referring to the drawings:

My present machine embodies a number of features which are old per se in the art, such as, for example, the paper feeding mechanism for the unglued wraps and the delivery mechanism for the glued wraps, and I have, therefore, illustrated and described such features with only sufficient detail to enable those skilled in this art to understand the construction and operation thereof.

The driving mechanism corresponds, substantially, to that shown in my prior Patent 1,744,244. As my invention resides more particularly in the

gluing mechanism and I will first describe the stencil mechanism.

1 designates the machine frame on which is pivotally mounted the gluing mechanism. A tubular coupling 3, see Figure 4, has a polygonally shaped aperture 4 at its outer end for operatively connecting it with its driving means in order to drive a paster feet roll 5. This paster feet roll 5 is made in sections and is provided at its driving end with a smooth roll 6 having a hub fixed to the driving coupling 3. The paster feet roll 5, at its opposite end, is provided with a smooth roll 7, provided with a hub 8 and gear 24, in which is journalled a shaft 9 retained in position by means of a collar 10. The opposite end of the shaft 9 is of reduced diameter and has a bearing in the tubular connection 3. The tubular connection 3 is journalled in one of the bearing brackets 11 carried by the machine frame. The shaft 9 has secured to it, by means of a pin 12, a paster feet carrier 13 which is provided with the dovetailed circumferentially extending slots 14 adapted to receive correspondingly shaped shoes 15 to which the stencils 16 are secured by means of fastening devices 17, illustrated as screws in threaded engagement with the shoes 15.

The hub 18 of the gluing roll section 6 has keyed to it a gear 19, by means of a key 20. The gear 19 meshes with a gear 21 carried by a shaft 22 journalled in the stencil carrier 13 and at its opposite end it is provided with a gear 23 which meshes with the gear 24 keyed to the hub 25 of the roll section 7. The shaft 22 is journalled in the bearing sleeve 26 which is fixed in position in the stencil carrier 13 by means of the pin 27, see Figure 4. The gluing roll section 6 has, in frictional engagement with it, a gluing ring 28 having the raised gluing face 29. In a similar manner, the gluing roll section 7 has, in frictional engagement with it, the gluing ring 30 having a circumferential gluing face 31. These gluing rings 28 and 30 effect the longitudinal gluing at the side margins of the wrap and can be positioned longitudinally of their roll sections to conform with the width of wrap which is being used.

The outer end of the gluing roll section 7 forms one part of a friction coupling and is recessed to provide a tapered clutch face 32 with which cooperates the tapered portion 33 of the clutch member 34 which latter is slidably mounted on the shaft 9. The shaft 9 is longitudinally slotted as at 35 to receive a shoe 36 which is fixed to the clutch member 34 by means of a fastening device 37. A spring 38 is interposed between the forward lug of the shoe 36 and an arm 39, which extends into the slot 40, and is pinned to the shaft 9 by means of a fastening device 41. It will be seen from Figure 4 that the arm 39 does not extend to the bottom of the slot in the shaft 9 so that the shoe 36 is capable of longitudinal sliding movement between the shaft 9 and the arm 39. The shoe 36 is provided at its outer end with an outer lug 42 having a stop in the form of a screw 43 which can be fixed in its adjusted position by means of a set screw 44. 45 designates a cam lever fulcrumed at 46 in the slot 40 and provided at one end with a cam face 47 adapted to contact with the adjustable stop 43.

70 The slotted end of the shaft 9 is enclosed by a housing 48 having a sleeve 49 extending into the adjacent bearing bracket 11 to contribute to form a bearing for the shaft 9. This housing 48 is apertured to receive a plunger 50, see Figures 6 and 7, connected at its lower end with a cam 51

and having its free end bevelled off as at 52. The plunger 50 travels in the path of a stop pawl 53 in the form of an L shaped arm pivoted at 54 to an L shaped block 55 slidably mounted in the housing. A spring 57 is interposed between the block 55 and the upper wall of the housing so that the tendency of such spring is to move the pawl 53 and the plunger 50 downwardly. The chamber of the housing has one side wall cut away, as at 58, to provide a space into which the pawl 53 can move so that the arm 39 is free to revolve and thereby the shaft 9 to which it is connected. To prevent the pawl 53 catching on the insert 59 I provide a spring pressed guide 60 having its free end bevelled, so that when the pawl 53 moves downwardly it will clear the upper sharp edge of the insert 59. The upper L shaped end of the block 55 overhangs a manually controlled member 56 in the form of a bar or strip of material which is provided with a recess 61, see Figure 7, forming a space into which the hook shaped end 62 of the cam lever 45 can move during the operation thereby releasing the slide 36 so that the spring 38 can move the clutch member 34 into clutched engagement with the roll section 7. In Figure 4 the hook shaped end 62 rests on the member 56.

The controlling member 56 is mounted out of alignment with the plunger 50 as will be clear from Figure 11, and is provided with an outwardly extending pin 114 which extends through a slot 63 in a cover plate 64 detachably connected with the housing 48. Beneath the controlling member 56 I provide an L shaped stop 115 secured in position by means of a fastening device 116, and the upper end of the plunger 50 overhangs the L shaped portion of such stop to thereby limit the downward movement of the plunger 50.

The controlling member 56 provides for the manual tripping of the stop pawl 53 and is controlled by a manually actuated lever 65, fulcrumed at 66 on the machine frame in proximity to the discharge end of the apron 67 which delivers the glued wrap to a wrapping machine or other desired place of utilization. When the grasping portion of the lever 65 is raised the rod 68, pivoted at one end to the free end of such lever, rocks the bell crank 69 on its fulcrum 70, see Figure 2, so that the bifurcated arm 71 which receives the pin 114 will raise the manually controlling member 56 and thereby the block 55 and the stop pawl 53. The rod 68 is slideable in the guide 72 between which and an abutment 73, on the rod, is interposed a spring 74 which tends to move the rod 68 into the position seen in Figure 2.

The cam 51 is actuated by a pin 75 which, as illustrated, is carried by and revolves in unison with a wrap feeding cylinder 76.

The gluing mechanism comprises a glue frame 77 pivotally mounted on a post 78 and provided with a grasping handle 79. The frame 77 is provided with a glue pot or reservoir 80, and into the glue in such reservoir extends a glue dipping roll 81 suitably journalled on the glue frame 77, see more particularly Figure 2. A glue trough 84, open at its outer end, has its lower side contacting with the periphery of the glue dipping roll 81, and the bottom of such side contacts with the periphery of the glue transfer roll 83 which is journalled in the brackets 82, see Figures 1 and 2. The top side of the trough 84 is movably carried by it and secured in adjusted position by means of the fastening devices 85 so that the space be-

tween the bottom of the upper side of the glue trough and the periphery of the glue transfer roll can be varied in accordance with the amount of glue which is to pass from the trough through such space to the glue applying roll 5. A squeeze or doctor roll 86 journaled on the glue frame 77 beneath the transfer roll 83 and contacts with the glue applying roll 5. Excess glue is removed from the doctor roll 86 by means of a scraper 87.

10 *The driving mechanism*

The driving mechanism is best seen in Figures 8 and 9 and is substantially the same as that shown in the Rider and Saatman Patent 1,744,-15 244.

88 is a motor, the shaft of which is operatively connected with a worm 89, meshing with a worm gear 90 fixed to a gear 91. The gear 91 meshes with a gear 92 keyed on a longitudinally adjustable shaft 93 having its inner end of a polygonal contour, as at 94, to engage the correspondingly shaped recess 4 of the glue applying roll 5. The shaft 93 is moved into clutch or declutched position by means of a manually actuated lever 95.

97 is the feed table, see Figure 2. 98 is the suction pump. 99 is the stripper bar, see Figures 1 and 4, adjustably mounted on the glue frame and provided with the strippers 100 adjustably mounted thereon.

30 The shaft of the glue applying stencil roll 5, see Figure 10, has a gear 101 fixed to it which meshes with an idler 102, which, in turn, meshes with a gear 103 which drives the shaft of the squeeze roll 86. This gear 103 meshes with a gear 104 on the shaft of the glue transfer roll 83. The shaft of the squeeze roll which carries the gear 103 is also provided with a gear 105 which meshes with an idler 106, which, in turn, meshes with an idler 107 which drives the gear 108 on the shaft which carries the dipping roll 81. The squeeze roll is journaled in the pivotally supported brackets 109, see Figure 2, which are provided with the adjusting screws 110 so that the squeeze or doctor roll can be adjusted relatively 45 to the glue applying paster feet roll 5.

The shaft of the dipping roll 81 is removable by upward displacement from its journal bearings and the same is true of the glue transfer roll 83. The squeeze or doctor roll is provided with 50 a sectional bearing so that such doctor roll may be removed for cleaning or other purposes, and the stencil roll is also provided with a sectional bearing having the nuts 111, see Figure 2, so that such bearing can be opened and the glue applying paster feet roll 5 can be removed and, if desired, replaced by a smooth gluing roll of any desired or conventional construction depending on the type of gluing which is to be done.

55 The feed cylinder 76, see Figure 3, is provided with a radial slot 112 in which is adjustably positioned a pin 113 which, when set, in a position corresponding to the fifteen inch graduation thereon, will allow the paster feet to be tripped a second time without pause between the first and second revolution. Pin 113 remains in a position corresponding to the fifteen inch graduation for all wraps fifteen inches in length and under. This fifteen inch length is the length of wrap which is equal to the circumference of the paster feet roll. It is obvious that for wraps fifteen inches and under two paster feet are used positioned circumferentially apart in the circumferential grooves 14 to suit the length of the wrap.

70 The second revolution in this case is simply

made to allow the wrap to be carried far enough to be completely stripped by strippers 100.

For wraps fifteen inches and over up to the capacity of the machine, only one front paster foot is used, which, when brought into operation by pin 113, will stencil the front end of the wrap, complete its revolution, pause a length of time corresponding to the amount the wrap exceeds the fifteen inch length and then tripped a second time by pin 113 to apply glue to the back end 10 of the wrap.

15 For this reason, the pin 113 is adjustable and provided with graduations 124, the setting of which corresponds to the length of the wrap to be run.

15 It is understood that the fifteen inch circumference mentioned is only referred to as an example of the condition that actually exists on the present machine. This will vary according to the circumference of the stencil roll used.

20 The stencil carrying portion of the glue applying roll, see Figure 1, is preferably provided with graduations 125 to facilitate the circumferential adjustment of the paster feet in accordance with the length of wrap which is to be glued.

25 I have deemed it unnecessary to illustrate and describe in detail all of the features of construction and operation as certain of them are now clearly understood by those skilled in this art and the general cycle is clearly set forth in Patent No. 1,744,244. I, have, therefore, illustrated in detail the paster feet roll and its controlling mechanism which forms more particularly the subject matter of this invention.

30 The operation will now be apparent and is as follows.

35 The wraps which are to be glued are placed on the counter weighted table 97. Assuming now that the glue frame 77 is in its closed position so that the shaft 93, see Figure 8, is in driving connection with the paster feet roll 5, the wraps will be progressively passed to the feed cylinder 76, being retained thereon by the conventional gripper mechanisms, which are, at the proper time, released in the conventional manner. Each wrap 45 is thus passed to the glue applying paster feet roll 5.

40 The glue dipping roll 81 feeds the glue from the glue pot 80 into the trough 84 which forms an auxiliary glue reservoir to feed the glue to the transfer roll 83 throughout its length.

45 The roll 83, rotating in the direction of the arrow, has its glue coating cut down to the proper thickness by the adjustable upper blade, adjustably fastened in 84 by clamping screws 85.

50 This is adjusted to allow the roll 83 to deposit a slight surplus of glue to the stencils and the gluing rings 28 and 30.

55 Once set, this adjustment need not be changed, but the desired amount of glue on the wrap is cut down by the squeeze or doctor roll 86 rotating in an opposite direction which wipes the paster feet and gluing rings free of the surplus glue.

60 The scraper 87 is for the purpose of cutting all the glue from the squeeze roll to allow it to present an absolutely clean surface when it comes in contact with the paster feet.

65 The adjustable gluing rings 28 and 30 are longitudinally adjusted on their roll sections. These rings have a driving fit on their roll sections, so that their gluing surfaces can be positioned in accordance with the width of the wrap which is to be glued, and the glue will be applied at opposite marginal portions throughout the length of the wrap. The paster feet 16 are circumferen- 75

tially adjusted in their slots 14 in accordance with the length of the wrap which is to be glued so that the transverse gluing will take place at the marginal end portions of a wrap. The glued wraps are delivered to the delivery apron 61. As the feed cylinder 76 revolves, the pin 75 cooperates with the cam 51 to move the plunger 50 upwardly.

The arm 39 is in the form of a tooth rounded at its bottom and terminating in a straight wall which latter is held in stopped contact with the face of stop pawl 53 under the frictional rotation of the rotating parts 6 and 7. The cam 51 operated from the feeding cylinder 76 is moved in an upward direction bringing the bevelled tooth 52 into engagement with 39 on the shaft 9 to which the stencil drum 13 is rigidly fastened by pin 12. By this tooth action the stencils or paster feet are started in a definite timed relation to the wrap on cylinder 76. It is evident that this positive motion would have short duration so that with a slight continued upward movement the friction clutch 34 is drawn into engagement with the constantly revolving member 1 by the hooked shaped end 62 of cam lever 45 dropping into the depression 61 and continuing into such engagement for a full revolution where the clutch is again disengaged by the contact of end 62 against member 56.

30 It is evident that when the upwardly moving plunger 50 makes contact with the tooth 39 the bottom edge of the stop pawl 53 must be in a position at the edge of the block 59 to allow it to swing out of the way as the continued upward movement of the plunger 50 starts the tooth 39 rotating the shaft 9.

The purpose of the member 56 with recess 61 is to hold the cam lever 45 in a position towards the center of shaft 9, in which position it is holding the clutch member 34 out of engagement with the rotating roll section 7.

With the upward movement of the plunger 50 the shaft 9, carrying cam lever 45, rotates to a position where the end 62 of the cam lever is in contact with the member 56 having recess 61, drops into the recess 61, allowing the friction clutch to engage to complete the entire revolution.

It will be apparent that if the lever 65, see Figure 2 is raised, the rod 68 is pushed against lever 69 which turns on its fulcrum 70 and raises pin 114, see Figures 15 and 16. This lifts the parts 56, 55 and 53. 53 is drawn out of contact with 39, and part 56 is moved out of contact with hook end 62 of lever 45. This permits spring 38 to move part 34 into engagement with part 7. As long as lever 65 is retained in raised condition the stencil organization revolves continuously until lever 65 is released. The purpose of actuating lever 65 is to remoisten the stencils in case the machine has been idle for a considerable period. During this period, wraps are not being fed. 56 and 53 are withdrawn at the same time and the clutch engages immediately. The lever 65 is only actuated when it is desired to remoisten the stencils.

The only time the member 61 moves is when manually operated by the lever 65.

It will now be apparent that I have devised a new and useful gluing machine which embodies the features of advantage enumerated as desirable in the statement of the invention and the above description, and while I have, in the present instance, shown and described a preferred embodiment thereof which will give in practice satisfactory and reliable results, it is to be un-

derstood that this embodiment is susceptible of modification in various particulars without departing from the spirit or scope of the invention or sacrificing any of its advantages.

Having thus described my invention what I claim as new and desire to secure by Letters Patent, is:—

1. In a gluing machine, a rotatable glue applying roll, having a normally stationary paster foot, intermittently revoluble with said roll, and means to cause said paster foot to revolve in timed relation with the feed of a wrap.

2. In a gluing machine, a rotatable glue applying roll having a relatively rotatable paster foot, intermittently revoluble with said roll, means to restrain the rotation of said paster foot, and means to release said restraining means.

3. In a gluing machine, a glue applying roll having a relatively movable paster foot, intermittently revoluble with its roll, means to revolve said roll, and means to render said paster foot effective or ineffective during the revolution of said roll.

4. In a gluing machine, a glue applying sectional roll, paster feet carried by one of said sections, glue applying rings longitudinally adjustable on other of said sections, means to cause intermittent revolution of a paster foot section during the revolution of the ring carrying sections, and means to revolve said ring carrying sections.

5. In a gluing machine, a glue applying sectional roll, paster feet carried by one of said sections and circumferentially adjustable thereon, glue applying rings longitudinally adjustable on other of said sections, means to cause intermittent revolution of a paster foot section during the revolution of the ring carrying sections, and means to revolve said ring carrying sections.

6. In a gluing machine, a glue applying roll comprising intergeared sections, paster feet adjustably carried by one of said sections, wrap feeding means, and means to cause the paster feet carrying section to remain stationary or to revolve in timed relationship with the wrap feeding means.

7. In a gluing machine, intergeared gluing rolls, driving means therefor, paster feet circumferentially adjustable on one of said rolls, means to automatically cause the paster feet carrying roll to remain stationary during the rotation of the other roll or to revolve with them, and means under the control of the operator to render the paster feet carrying roll operative.

8. In a gluing machine, a glue applying roll comprising smooth roll sections, glue applying rings longitudinally adjustable on said smooth roll sections, paster feet supported to be circumferentially adjustable, a shaft carrying the paster feet support, a clutch longitudinally slidably on said shaft but incapable of relative rotation and cooperating with one of said roll sections to lock the shaft with respect to it, means to revolve one of said roll sections, and means to automatically control the engagement and disengagement of the clutch to cause the paster feet to remain stationary for a predetermined interval during the revolution of said roll sections.

9. In a gluing machine, a glue applying roll, including a revolvable paster foot carrier, a feed cylinder to feed wraps into operative relation with said glue applying roll, means to revolve said roll, and means carried by said feed cylinder to cause said paster foot carrier to remain stationary or

to revolve in timed relationship with said feed cylinder.

10. In a gluing machine, a glue applying roll having a revolute paster foot carrier, wrap feeding means to feed wraps into operative relation with said roll, a cam controlling member carried by said feed cylinder, a second cam controlling member circumferentially adjustable on said feed cylinder, and means controlled by said cam controlling members to cause said paster foot carrier to remain stationary or to revolve in timed relationship with said wrap feeding means.

11. In a gluing machine, the combination with a glue dipping roll and a glue transfer roll of a trough to receive glue from said glue dipping roll, and there being a feeding space between one side of the trough and the glue transfer roll.

12. In a gluing machine, the combination with a glue dipping roll and a glue transfer roll of a trough to receive glue from said glue dipping roll,

and there being a feeding space between the trough and the glue transfer roll, and means to vary the dimensions of said feeding space.

13. In a gluing machine, wrap feeding means, a rotatable glue applying roll, means to revolve said roll, means to feed glue to said roll, and means in timed relation with the wrap feeding means for rendering portions of said roll ineffective to apply glue to a wrap for a predetermined interval without rendering ineffective other portions of said roll to apply glue.

14. In a gluing machine, wrap feeding means, a rotatable glue applying roll, means to revolve said roll, means to feed glue to said roll, and means controlled in timed relationship with the feed of a wrap to render portions of said roll ineffective to apply glue to a wrap, for a predetermined interval without rendering ineffective other portions of said roll to apply glue.

WALTER A. SAATMAN. 20
